FIG. 1 is a front, top, and right-side perspective view of the slide clamp showing our new design;
FIG. 2 is a front elevation view thereof;
FIG. 3 is a back elevational view thereof;
FIG. 4 is a right-side elevational view thereof;
FIG. 5 is a left-side elevational view thereof;
FIG. 6 is a top plan view thereof;
FIG. 7 is a bottom plan view thereof;
FIG. 8 is a front, top, and right-side perspective view of another embodiment of a slide clamp, showing our new design;
FIG. 9 is a front elevation view thereof;
FIG. 10 is a back elevational view thereof;
FIG. 11 is a right-side elevational view thereof;
FIG. 12 is a left-side elevational view thereof;
FIG. 13 is a top plan view thereof; and,
FIG. 14 is a bottom plan view thereof.

The broken lines show portions of the design that form no part of the claimed design
